UNITED STATES PATENT OFFICE.

GEORGE W. STORER, OF PHILADELPHIA, PENNSYLVANIA.

PNEUMATIC DISPATCH APPARATUS.

SPECIFICATION forming part of Letters Patent No. 251,654, dated December 27, 1881.

Application filed September 27, 1881. (No model.)

To all whom it may concern:

Be it known that I, GEORGE W. STORER, a citizen of the United States, residing in Philadelphia, Pennsylvania, have invented certain

5 Improvements in Pneumatic Dispatch Apparatus, of which the following is a specification.

My invention relates more especially to pneumatic apparatus for transferring cash, bills, &c., in carriers through tubes between the counters 10 of salesmen and cashiers' desks in stores, although it may be applied on a larger scale for the transmission of packages between distant points; and the object of my invention is to economize power by the use of compressed air 15 to force the carriers through the tubes instead of maintaining a vacuum in the same, and by using in connection with the tubes the appliances described hereinafter, whereby no more compressed air than is absolutely required to 20 propel a carrier to its destination will be consumed.

In the accompanying drawings, Figure 1 is a perspective view, illustrating the principle on which my invention is based; Fig. 2, a view 25 showing my invention in its simplest form. Fig. 3, Sheet 2, is a side view, on a larger scale and partly in section, of my improved apparatus in a more complete form; Fig. 4, a vertical section on the line 1 2 of Fig. 3; Fig. 5, a vertical 30 section on the line 3 4 of Fig. 3; Fig. 6, Sheet 1, views of the carrier, drawn to a reduced scale; and Fig. 7, a perspective view of one of the valves of the apparatus.

In Fig. 1, A represents part of a pneumatic 35 tube communicating with a receiving-box, B, having a door, D, opening inward. A pipe, h, which receives compressed air from a reservoir and communicates with the box B and pneumatic tube, is furnished with a suitable 40 cock or valve. After introducing the carrier, referred to hereinafter, through an opening in the box, the said opening is closed by the door and the cock or valve opened, when the carrier will be propelled along the tube by the compressed air.

It should be here understood that I do not claim the device above described, and shown in Fig. 1, which has been introduced by way of preliminary explanation, my invention in its 45 simplest form being illustrated in Fig. 2, in

which the valve is placed under the control of the door, the pin of the hinge being connected to the spindle of a valve, preferably a balanced valve, and the door being self-opening inward, so that when the said door is closed 55 after the introduction of the carrier into the box the valve will be opened and air under pressure will pass into the box and propel the carrier along the tube, the air keeping the door closed until the carrier escapes from the end 60 of the tube, when, pressure being removed, the door will automatically open and close the valve, thereby cutting off the compressed air from the box. I prefer, however, to adopt the plan which is shown in the enlarged views, Figs. 65 3, 4, 5, 6, and 7, which I will now proceed to describe.

A is a portion of the pneumatic tube, which, for such purposes as the conveyance of cash, bills, &c., in stores, is about two and a half 70 inches in diameter. B, the receiving-box, is situated at one end of the tube and communicates therewith, the under side of the box being rounded to coincide with the said tube. There is an opening, a, in front of the box for 75 the reception of the carrier, which forms no part of my present invention, and may be briefly described as two semi-cylindrical parts hinged together, as shown in Fig. 6, so as to be opened. There is a disk or piston at one end of one part 80 of the carrier and a similar disk at the opposite end of the other part of the carrier, so that when the latter is closed it will consist of a cylindrical case with a piston at each end, the pistons, which are larger in diameter than the 85 case, being of yielding material and fitting snugly but so as to move freely in the tube A.

The door D is so hinged at its upper edge by a pin d to the box B that it can be moved to the position shown by plain lines against 90 the top of the said box, when the opening a will be exposed for the admission of the carrier, or to the position shown by dotted lines, when the opening will be closed, in all cases, however, the door being combined with a 95 spring, weight, or other device, so as to be self-opening. In the present instance the pin d, which passes through arms e on the door and through lugs f on the case, thereby forming a hinge, is surrounded by a spiral spring, one 100

end of the wire being fastened to the case A, the other end being secured to the pin *d* or to the door, for it should be understood that the pin moves with the door, as it is secured to the 5 arms *e e* of the same.

The branch *h* of a valve-chest, *G*, is secured in any suitable manner to and communicates with the interior of the receiving-box *B*, the other branch, *h'*, of the chest being in communication with a reservoir in which air at a constant pressure of, say, five pounds per square inch is maintained.

Different kinds of valves may be used for opening and closing the communication between these two branches of the chest, the valve consisting in the present instance of a cylinder, *i*, having an opening, *i'*, and terminating in a piston, *m*, adapted to a cylinder, *k*, projecting from the chest. The valve fits loosely 15 in the chest, as also does the piston in the cylinder—that is to say, while they fit with comparative accuracy the piston and valve should be at liberty to move with freedom; and it is essential that there should be a constant 20 pressure of air beneath the piston and that there should be a contracted passage or passages in the latter for the admission of air from the space below the piston to the space above the same, this contracted passage being preferably 25 formed by grooving the edge of the piston, so that air can pass through the groove, as indicated by the arrow, Fig. 3.

There must be on the cylinder above the piston a valve, *H*, under the control of the door 30 *D*, and the valve must be such that the instant the door is closed the space in the cylinder above the piston will have a free communication with the external air and that the moment the door is opened this communication shall be 35 cut off. A hollow cylindrical valve, *p*, Fig. 7, is used in the present instance, and this is adapted to a hollow cylindrical seat, *g*, in the top of the cylinder *k*, the valve having an elongated slot, *t*, corresponding with a similar slot 40 in the top of the cylinder. An arm, *w*, on the valve is connected to an arm, *x*, on the pin *d* of the door-hinge by a rod *y*. Other devices 45 for placing the valve under the control of the door will readily suggest themselves.

When the pneumatic tube is not in use the door *D* will be open, the valve *p* will be closed, as also will the valve *i*, the air above the piston being exerted on a larger area than below. Hence the compressed air is cut off from 50 the receiving-box and pneumatic tube. When the latter has to be used, however, the attendant places the carrier in the box and at once closes the door *D*, when the valve *p* will be opened and the piston, the upper surface of 55 which is thus relieved from pressure, will at once be forced upward, carrying with it the valve *i* and admitting compressed air to the 60

box *B* and pneumatic tube *A*, and the carrier will be forced along the latter, the door *D* being meanwhile retained in its closed position 65 by the pressure of air; but when the carrier escapes from the end of the tube the pressure within the receiving-box will cease, the door *D* will be opened by the spring, the valve *p* will be closed, and the piston *m*, with its valve, 70 will at once fall, thereby cutting off the compressed air from the pneumatic tube. The opening and closing of the valve *i* is almost simultaneous with the opening and closing of the door *D*, so that there is no material waste 75 of compressed air.

In ordinary pneumatic dispatch apparatus a constant vacuum or partial vacuum is maintained within a system of pneumatic tubes, and this demands the uninterrupted consumption of power, whereas the power required to operate the carrier by compressed air in my apparatus is intermittent—that is to say, the power is exerted for the length of time only required to propel the carrier through the 80 tube. Another objection to vacuum apparatus is the liability of the carriers to stick in the tubes, owing to the low pressure to which they are subjected; and a further objection, during the winter months, is the 85 exhausting of large volumes of heated air from rooms or apartments in which the apparatus is situated. These objections are effectually overcome in compressed-air apparatus such as that described, as in such apparatus any 90 desired pressure of air may be used, and the volumes of air may be either warmed or cooled by artificial means previous to being forced through the tubes.

I claim as my invention—

1. The combination of the pneumatic tube, the receiving-box having a self-opening door, and a valve controlled by the door and adapted to govern the flow of air, substantially as 100 described.

2. The combination, in pneumatic dispatch apparatus, of the following elements, namely: a pneumatic tube, a receiving-box provided with a self-opening door, a valve-chest communicating in one direction with a reservoir containing compressed air and in the other direction with the receiving-box and pneumatic tube, a valve for opening and closing the said communication, a piston attached to the valve and adapted to a cylinder, and a 105 supplementary valve under the control of the door, all substantially as set forth.

In testimony whereof I have signed my name to this specification in the presence of two subscribing witnesses.

GEORGE W. STORER.
